UNITED STATES PATENT OFFICE

WILLIAM M. UPDEGRAVE, OF JOHNSTOWN, PENNSYLVANIA

MEANS FOR TREATING AND EXERCISING THE OCULAR MUSCLES

Application filed March 18, 1930. Serial No. 436,824.

This invention relates to a method and means for testing, exercising and developing the ocular muscles of the eyes and to stimulate the intrinsic or ciliary muscles, resulting in a perfect balance of the muscles, eliminating eye strain and the resultant defective vision.

Another object of the invention is to provide means to develop the external muscles of the eye by moving rotatable objects before the eyes, causing the eyes to pull against the muscles, when the eyes follow the movements of the objects.

A further object of the invention is to provide a machine of this character having means to cause the objects supported thereon to move in various directions and in various ways to exercise the muscles for curing various defects in vision.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is an elevational view of a machine constructed in accordance with the invention.

Figure 2 is a plan view thereof.

Figure 3 is a elevational view illustrating the opposite side of the device.

Figure 4 is a bottom view of the device.

Figure 5 is an elevational view illustrating the manner of supporting a chart.

Figure 6 is an elevational view of a pinwheel, showing the manner of supporting the pinwheel.

Referring to the drawings in detail, the reference character 5 designates the base plate of the device, which is provided with an upstanding end portion 6. Secured to the base plate 5, is a bracket 7 through which the shaft 8 extends, the bracket being provided with bearings to receive the shaft.

The shaft 8 is provided with a head 9 fitted in the socket 10 at the upper end of the shaft

11 to secure the shaft 8 in position. At the upper end of the shaft 8 is a gear 9' which is engaged by the rack bar 10 that is eccentrically connected to the gear 11', as clearly shown by Figure 4 of the drawings.

The gear 11 is formed with internal teeth which are in mesh with the pinion 12 mounted at the lower end of the shaft 13 that extends through the tubular bearing 14 mounted on the base 5.

Secured to the upper end of the shaft 13, is a gear 15 which is in mesh with the worm 16 formed on the horizontal shaft 17, which shaft carries the gear 18, the shaft being mounted in a bearing formed on the casting 18'. Gear 18 meshes with pinion 19 which is secured to one end of the shaft 20 to which shaft the gear 21 is secured, the gear 21 being in mesh with the pinion 22, mounted on the shaft 23 of the motor 24. On one end of the shaft 17 is an arm 25 to which the rack bar 26 is pivotally connected, the rack bar operating through the bearing 27. As shown, the rack bar 27 is in mesh with the pinion 28 that in turn is mounted on the shaft 29, which is square to fit in a square opening of the disk 30, so that the disk may be rotated in one direction, for a predetermined distance, and returned, reversing the movement of the disk, and providing a movement of the disk which is substantially oscillatory.

The opposite end of the shaft 17 is square to fit in the square opening in one end of the tubular arm 32, into which the rod 33 extends, there being provided a set screw 34 for securing the rod in position. Thus it will be seen that the rod 33 may be adjusted to various positions with respect to the tubular arm 32.

The free end of the rod 33 extends laterally as at 35 where it provides a support for the chart 36, the chart being secured to the rod 33 by means of the straps 37, so that the chart will hang vertically as the rod and arm are rotated.

Pins 38 and 39 respectively extend from the disk 30 and provide supports for the charts 40 which are mounted on the hangers 41 in such a way that the disk may rotate, and the charts held in vertical positions.

As shown by Figure 6, the pinwheel which

is indicated by the reference character 38' is mounted on the rod 39' that in turn is positioned in the end of the tubular arm 32, in place of the rod 33, so that the rod 39' may 5 be adjusted to increase or diminish the diameter of the circle or path in which the pinwheel moves. It is contemplated to view the pinwheel through prism lenses placed before the patient's eyes in different positions, to 10 cause exertions of the weak muscles of the eyes resulting in the muscles pulling harder, which will have a tendency to increase the strength of the muscles.

From the foregoing it will be obvious that 15 due to the construction shown and described, the frame of the device may be rotated in a horizontal plane, in one direction, and reversed, repeating such movements to exercise the eyes when viewing the charts or objects 20 supported by the device.

The disk 30 may be removed from the shaft 27 and the arm 32 substituted therefor, depending on the treatment of the eyes of the person. When in operation the entire instrument oscillates approximately 180 degrees, while the pinwheel or disk are in motion, and since the disk 30 makes only a half turn, it is impossible for a patient to strain the eye muscles, as the patient cannot concentrate 25 when viewing a moving object, allowing the eyes to remain in a relaxed condition which has a tendency to increase the acuity of vision.

I claim:

35 1. A device for operating optical charts for eye testing purposes, comprising a pivoted base, means for operating the base in a horizontal plane, gearing mounted on the base, a supporting member supported by the gearing and adapted to oscillate in a vertical plane, and pivoted members mounted on the supporting member.

40 2. A device for operating optical charts for eye testing purposes, comprising a pivoted base, a support for the base, a gear on the support for the base, a rack bar carried by the base and meshing with the gear to cause the base to oscillate, a shaft on the base, means for causing the shaft to oscillate, and 45 a supporting member on the shaft to oscillate therewith, and pivoted members on the supporting member.

45 3. A device for operating optical charts for eye testing purposes, comprising a pivoted base, a support for the base, means for oscillating the base in a horizontal plane, gearing on the base, a shaft operated by the gearing, a disk-like support mounted on the shaft, and movable objects mounted on the disk-like 50 support.

55 4. A device for operating optical charts for eye testing purposes, comprising a pivoted base, gearing on the base, means for operating the gearing to cause the base to oscillate in a horizontal plane, a shaft on the base,

said gearing adapted to oscillate the shaft, and a supporting disk mounted on the shaft for supporting objects to be used by the patient.

5. A device for operating optical charts for 70 eye testing purposes, comprising a pivoted base, gearing on the base, a horizontally disposed shaft mounted on the base and operated by the gearing, interchangeable members on the ends of the shaft to move with the shaft, 75 and said interchangeable members carrying objects to be viewed by the patient under treatment.

6. A device for operating optical charts for 80 eye testing purposes, comprising a pivoted base, means for oscillating the base in a horizontal plane, gearing mounted on the base, a shaft oscillated by the gearing, a tubular arm removably mounted on one end of the shaft, a rod adjustably mounted within 85 the tubular arm, said rod having a right angled extremity, and a movable member mounted on the right angled extremity of the rod, to be viewed by the patient.

In testimony that I claim the foregoing as 90 my own, I have hereto affixed my signature.

WILLIAM M. UPDEGRAVE.
